SAFE LOCK

Clarence L. Dodd, Lindsay, Okla.

Application January 29, 1947, Serial No. 724,950

5 Claims. (Cl. 70—1.7)

1

This invention relates to improvements in safe locks and more particularly to an improved anti-robery lock which becomes operative to prevent opening of the safe door only when the normal door locking apparatus has been damaged in an attempt to forcibly open the safe.

The usual small or medium size office safe has its door provided with a combination lock, a handle and a set of dead bolts along one or both vertical edges of the door. The handle is operatively connected with the dead bolts in such a manner that turning the handle will move the dead bolts between their retracted and extended positions, these bolts being held in their extended or locking position by a suitable detent controlled by the usual combination lock so that the bolts may be withdrawn from their locking position only when the lock has been operated according to the proper combination.

Unauthorized persons attempting to open such safes by force usually proceed by breaking off the knob and outer plate of the combination lock and then driving this lock inwardly with a punch. When the combination lock has been driven out of its operative position the dead bolts are released and the safe door may be opened by turning the handle in the proper direction.

Various attempts have been made to provide suitable means, operative only when the combination lock has been driven out or damaged, to automatically engage the dead bolts or the locking bar to which the dead bolts are connected, and preclude movement of the dead bolts by the handle to unlock the safe door. These previously proposed devices have not met with any high degree of commercial success as they are either too expensive and difficult to install, are not adaptable to the type of safe generally used in offices and small business establishments, are not positive in their operation and hence do not adequately protect the contents of the safe in case of an attempted robbery, or may be easily released by a burglar by the simple expedient of drilling a hole through the safe door in any position over a considerable area of the door and inserting an instrument through the hole to move the emergency or safety latch out of its latching position, or render it impossible for anyone to reopen the safe door once the emergency latch has been set without completely destroying the safe.

It is an object of the present invention to provide an improved anti-robery lock for safes of the type usually located in business offices or small business establishments, which latching

2

device is inexpensive, easy to install, positive in operation, non-releasable by an unauthorized person but releasable by an authorized person so that after an attempted robbery the safe door may be opened without the necessity of seriously damaging or destroying the safe.

Other objects and advantages will become apparent from a consideration of the following description in conjunction with the accompanying drawings, wherein:

Fig. 1 is an elevation of the inner side of a conventional safe door showing the safe locking mechanism without the improved anti-robery locking or latching device applied thereto;

Fig. 2, a view similar to Fig. 1 showing the application to the conventional safe door of anti-robery locking means illustrative of the invention with the locking means in its normal or inoperative position;

Fig. 3, a perspective view of the movable bar component of the anti-robery locking means shown in Fig. 2;

Fig. 4, a fragmentary transverse sectional view to an enlarged scale on the line 4—4 of Fig. 2 showing the anti-robery locking means in inoperative condition;

Fig. 5, a sectional view similar to Fig. 4 showing the anti-robery locking means in operative condition;

Fig. 6, a diagrammatic perspective view of a fragmentary portion of the improved safety lock showing latch means which prevent release of the safety lock by an unauthorized person once the safety lock has been actuated to operative position, the latch means being shown in their normal or inoperative position;

Fig. 7, an elevational view of a fragmentary portion of the safety or anti-robery locking means showing the latch means illustrated in Fig. 6 in its extended or operative position;

Fig. 8, a view similar to Fig. 7 showing the latch means in the position incident to its being retracted after an attempted robbery during which the safety lock has been set;

Fig. 9, a fragmentary view to an enlarged scale showing the parts of the anti-robery device in inoperative position and with parts in section for greater clarity; and,

Fig. 10, a perspective showing the latch operating rod.

With continued reference to the drawings and particularly to Fig. 1, the safe door, generally indicated at 10, is provided with the usual stepped or labyrinth edge 11, to which is secured a thick outer plate 12 of durable material such as iron

or steel. The door is supported on the safe by means of suitable hinges 13 and is provided with locking bolts or dead bolts 15 and 16 along the hinge edge and 17 and 18 along the free edge. The bolts 15 and 16 may be fixed in position and engage with the associated portion of the safe so that this edge of the door cannot be removed by disconnecting the hinges. The bolts 17 and 18 are slideable and are attached to a locking bar 19 which is substantially parallel to the vertical free edge of the door. The inner edge of the door is provided with an overlapping lip or flange 20 and the locking means is disposed between this flange and the inner surface of the plate 12. The flange 20 normally carries an inner or finish plate 15 not illustrated which covers the door locking mechanism.

The inner end of a handle 21 is engaged in a suitable slot in the locking bar 19 and is operative to move the locking bar toward and away from the corresponding edge of the door, extending or retracting the bolts 17 and 18 between their door locking and door releasing positions. The locking bar 19 is guided by an arm 22 offset from the inner edge of the bar, extending substantially at right angles therefrom and having a slot through which extends a guide pin 23 secured to the inner side of the plate 12. This locking bar also has extending therefrom an abutment in the form of an arm 24, the outer end of which is engageable by one end of a pivoted detent 25. The other end of the detent engages notched discs 26 on the safe combination lock. When the discs of the combination lock are all moved to the proper position the detent 25 is released to turn about the pivotal mounting 27 and clear the end of the abutment arm 24 so that the locking bar and the dead bolts 17 and 18 carried thereby may be moved by the handle 21 to their retracted position to unlock the door. The combination lock is enclosed in a suitable housing, as indicated at 28.

In the usual safe construction if the combination lock together with the housing 28 and detent 25 is driven inwardly through the door, the detent 25 will be moved out of position to engage the abutment arm 24 and the door may then be released by turning the operating handle 21. Since explosives, cutting torches, and similar devices are expensive, difficult to obtain and operate and apt to cause detection of the robbery, most persons attempting to burglarize an office type safe will proceed in the manner indicated above by first breaking off the combination lock knob and then driving the combination lock inwardly to free the locking bar.

The application of the improved anti-robery or safety latch is clearly shown in Fig. 2. An elongated bar 29 is provided at its ends with bolt-like extensions 30 and 31 which extend through plates 32, 33, 34 and 35 secured within the safe door. The plates 32 and 34 are preferably secured to the door by suitable means such as welding or brazing and have their ends disposed between the inner surface of the outer door plate 12 and the overlying flange 20. The plates or rods 33 and 35 bear upon and are slideable relative to the corresponding plates 32 and 34.

Abutment members 37 and 38 are secured to the opposite or hinged edge portion of the door and carry corresponding bar or link members 39 and 40 secured thereto by a suitable rod member 41 having externally screw threaded ends passing through the abutments and the corresponding links and secured thereto by oppositely disposed

nuts threaded onto the screw threaded end portions of the rod.

The link or rod member 39 is connected to its opposite link or rod member 33 by a turn buckle 42 and the link member 40 is connected to its opposite link or rod member 35 by a similar turn buckle 43.

By means of the turn buckles 42 and 43 the position of the safety locking bar 29 relative to the locking bar 19 can be accurately adjusted so that when the bar 29 is tilted about its pivotal connections 30 and 31 its outer edge 44 will pass behind the inner edge 45 of the locking bar 19 and preclude movement of the locking bar in a direction to retract the bolts 17 and 18.

The bar 29 is secured in proper vertical position by nuts screw threaded onto the pivotal members 30 and 31 outside of the corresponding supporting bars 32 and 34. Pressure exerted upon the locking bar 19 by the handle when the safety bar 29 is in operative position is transmitted through the members 33, 35, 39 and 40 and the turn buckles 42 and 43 to the hinged edge of the door so that the safety bar will adequately resist any pressure that may be placed upon it by force applied to the handle 21.

An arm 46 is secured to the bar 29 for vertical adjustment and extends outwardly from this bar in position to overlie the combination lock housing 28 so that if the combination lock or the housing 28 are driven inwardly of the door they will contact the arm 46 and force it in the same direction thereby turning or tilting the bar 29 about its pivotal mountings from the position shown in Fig. 4 to the position shown in Fig. 5, in which last position its edge 44 engages behind the adjacent edge 45 of the locking bar 19.

A trigger arm 47 also extends outwardly from the bar 29 but in the opposite direction from the arm 46 and carries at its outer end a pivotally mounted trigger 48 which contacts the adjacent side of locking bar 19 as the bar 29 is tilted to its fully operative position. This trigger member is operatively connected with latching means carried by the bar 29 and fully illustrated in Figs. 6, 7, and 8.

This latching means comprises a hollow rectangular housing 49 slidably mounted in a rectangular recess 50 provided in the bar 29 and opening to the edge 44 thereof. A plurality of latch pins, as indicated at 51, 52 and 53, are slidably mounted in the housing 49.

While three such latch pins have been illustrated, it is to be understood that one or any greater number of such pins may be used without in any way exceeding the scope of the invention.

These pins 51, 52 and 53 each have a cylindrical outer end portion of somewhat reduced diameter and a cylindrical inner end portion of enlarged diameter providing intermediate the length of each pin an annular shoulder, as indicated at 54, 55 and 56 respectively in Fig. 6. The larger end portions of the pins are hollow and receive respective compression springs, one of which is indicated at 57 for the pin 52, which springs tend to project the pins outwardly through that face of the housing 49 which is parallel to the edge 44 of bar 29.

A common detent 58 is pivotally connected along one edge to the housing 49 by a suitable hinge connection 59 and when in its normal position engages the shoulders 54, 55, and 56 to retain the pins 51, 52 and 53 in their retracted position against the pin projecting force of the re-

spective compression springs, as illustrated in Fig. 4. This detent has an outwardly extending arm 61 which is engaged by the corresponding angularly extending end 62a of an L-shaped rod 62, illustrated in Figs. 4 and 5, which extends through a suitable bore in the arm 47 and is engaged at its opposite end by the pivoted trigger 48.

With this arrangement, when the safe combination lock is driven in and the safety bar 29 is consequently tilted, the trigger 48 will strike the adjacent side of bar 19, as shown in Fig. 5, and move the rod 62 inwardly, which rod acting through the arm 61 moves the detent 58 to release the latch pins 51, 52 and 53. These pins thereupon engage behind the locking bar 19, as shown in Fig. 5, and the safety locking bar 29 cannot then be moved out of engagement with the locking bar 19 until these pins are retracted. If the person attempting to burglarize the safe now drills a hole through the door in any position which will permit him to insert a tool to engage the bar 29, he still cannot turn this bar out of the way as it is held in operative engagement with the locking bar by the extended or projected latch pins.

As an additional precaution, the arrangement is such that after the rod 62 has moved the detent sufficiently to release the pins it subsequently passes over the end of arm 61 releasing the detent and permitting spring 63 to move the detent back to a position in which its edge opposite the hinge connection 59 engages behind the enlarged end portions of the pins and prevents the pins from being retracted.

After the safety or emergency lock has thus been tripped it is not possible to open the safe door until the latch pins have been retracted and the bar 29 returned to its inoperative position. For this purpose a key operated cylinder lock 64 is mounted in recess 50 in bar 29 by suitable means such as arm 65 and provided with a radially extending cam 66 engaging the adjacent side of housing 49 and a depending member 67 disposed at the opposite side of the lock from the housing. When this lock is rotated by a suitable key the cam 66 will move the entire latching mechanism comprising the housing 49, pins 51, 52 and 53 and detent 58 backwardly in the recess 50 to the position illustrated in Fig. 8, which releases the pins from their engagement with the locking bar 19. Lateral pressure on the bar 29 will then rotate this bar to release the locking bar 19, whereupon the safe door may be opened by the handle 21.

The lock 64 is set at an angle to the bar 29 such that its center line is substantially perpendicular to the surface of plate 12 when bar 29 is in its operative position as shown in Fig. 5 and is behind the door plate 12, there being nothing on the outside of the door indicating the position of this lock. This information is available however to an authorized person and an exact measurement can be made to locate the center of a hole which will permit insertion of the key into the lock 64. After the location of this center has been determined a hole is drilled through the door plate and the proper key inserted in the lock to release the emergency locking device. Thus, while the emergency locking device cannot be released by an unauthorized person, it can be released and the door opened by an authorized person without other damage to the safe than the drilling of a hole through the door. As it is usually necessary to obtain a

new door anyway after such an attempted burglary, this is not an objectionable feature and the remainder of the safe can be salvaged and a new door applied thereto.

5 The supports 32 to 40 inclusive for the safety locking bar are easily inserted in a conventional safe door and, in the case of an insulated door, require the removal of only a small portion of the insulating material. The safety locking bar 10 can be easily and accurately adjusted to its proper operative position and is positively supported so that no force applied through the lock 15 operating handle is sufficient to move this bar when it is in its operative position. The safety or emergency locking means cannot be released except by a person having exact knowledge of the location of the key lock and having a proper key to fit this lock but can be released by such 20 a person without material additional damage to the safe.

It will be obvious to those skilled in the art that 25 various changes may be made in the invention without departing from the spirit and scope thereof and therefore the invention is not limited by that which is shown in the drawings and described in the specification but only as indicated in the appended claims.

What is claimed is:

30 1. In a safe door having slidable bolts in at least one edge portion thereof, a locking bar connected with said bolts, a handle pivoted in said door and operatively connected with said locking bar to move said bolts, a combination lock carried by said door, and a detent actuated by said combination lock to hold said locking bar in position with said bolts extended or to release said locking bar for retraction of said bolts by said handle; a safety bar supported on said door 35 substantially parallel to said locking bar by pivotal connections at the ends thereof; an arm on said safety bar overlying said combination lock and operative upon driving in of said lock to tilt said safety bar to a position in which one edge thereof engaged behind said locking bar to restrain said locking bar against bolt retracting movement; latch means carried by said safety bar engageable with said locking bar to hold said safety bar in tilted position; a trigger arm on said 40 safety bar; a trigger carried by said trigger arm movable by contact with said locking bar when safety bar is tilted, to release said latch means; and a key operated lock within said door operative to retract said latch means and permit disengagement of said safety bar from said locking bar when a key is inserted therein through a hole drilled in said door.

2. In combination with a safe door having an outer plate supporting movable bolts, a locking bar connected to said bolts, a handle operatively connected with said locking bar to move said bolts, a combination lock and detent engageable with said locking bar to prevent retraction of said bolts by operation of said handle; a safety 45 latching bar pivotally supported by said door in position when tilted to engage behind said locking bar and prevent retraction of said bolts; an arm attached to said safety bar and overlying said combination lock to tilt said safety bar into locking engagement with said locking bar if said combination lock is forcibly displaced; latch means carried by said safety bar to engage behind said locking bar and prevent disengagement 50 of said safety bar therefrom; means releasably

holding said latch means in inoperative position, trigger means carried by said safety bar operative to release said latch means when said safety bar is tilted; and key operated lock means accessible only through a hole drilled through said outer door plate at a predetermined position operatively associated with said latch means to release said latch means and move said safety bar out of engagement with said locking bar.

3. An anti-robery safety lock for an office safe comprising upper and lower adjustable supports secured to the inner side of the safe door; a safety bar substantially parallel to one edge of said door pivotally mounted at its ends on said supports; an arm projecting outwardly from said safety bar over the safe combination lock to rotate said safety bar to a position in which it engages behind the locking bar of the safe if the combination lock is forcibly displaced; latch means carried by said safety bar engageable with said locking bar when said safety bar is tilted into operative position, and key controlled lock means accessible only through a hole drilled in an exactly known location in said door operatively associated with said latch means to release the same from engagement with said lock bar.

4. An anti-robery lock for a safe to prevent opening of the safe door after the safe combination lock has been driven out of locking position comprising a bar pivotally secured at its ends to the safe door and located inside the door in position to tilt into edge to edge engagement with the locking bar carrying the locking bolts; an arm on said pivoted bar overlying the combination lock to tilt said pivoted bar into engagement with said locking bar; normally retracted latch means carried by said pivoted bar; and trigger means carried by said pivoted bar operative upon tilting of said pivoted bar to release said latch

10
15
20
25
30
35
40

means to engage with said locking bar and maintain said pivoted bar in engagement therewith.

5. In combination with a safe door including manually controlled door locking means, auxiliary anti-robery locking means mounted on said door for movement to and from an operative or an inoperative position, said auxiliary locking means when in inoperative position permitting manual operation of said door locking means and when in operative position having means for engaging a portion of said door locking means preventing operation thereof to unlock said door, means on said auxiliary locking means engageable by said door locking means upon abnormal displacement thereof to move said auxiliary locking means to operative position, latch means on said auxiliary locking means operable by movement thereof to operative position to automatically and positively latch said auxiliary locking means in operative position and key controlled locking means accessible only through a hole drilled at an exact predetermined location through said door having means engaging said auxiliary locking means to move the same to inoperative position upon actuation of said key controlled locking means.
